CEMENTED SHOE CONSTRUCTION

Henry B. Gorman, Lynchburg, Va., assignor to
 Compo Shoe Machinery Corporation, New York,
 N. Y., a corporation of Delaware

Application March 6, 1935, Serial No. 9,601

2 Claims. (Cl. 12—142)

This invention relates to the manufacture of cemented shoes, and more particularly to the manner of bonding the outsole of such a shoe to the upper.

5 A general object of the invention is to provide an improved cemented shoe structure wherein any tendency of the outsole to peel away from the upper is circumvented.

10 A further object is to provide an improved outsole for cement attachment to a lasted upper.

Another object is to provide a method of preventing the outsole of a cemented shoe from peeling away from its upper.

15 Yet another object is to provide a cemented shoe having a stronger, more permanent bond between the outsole and upper.

Other objects of the invention will in part be obvious and will in part appear hereinafter.

20 The invention accordingly comprises the several steps and the relation of one or more of such steps with respect to each of the others, and the article possessing the features, properties, and the relation of elements, which are exemplified in the following detailed disclosure, and the scope 25 of the application of which will be indicated in the claims.

25 For a fuller understanding of the nature and objects of the invention reference should be had to the following detailed description taken in connection with the accompanying drawing, in which:

30 Fig. 1 is a perspective view of an outsole embodying the principles of the present invention; and

35 Fig. 2 is a fragmentary transverse sectional view across the forepart of a shoe to which the outsole of Fig. 1 has been attached.

40 In the manufacture of cemented shoes the outsole is united to the bottom of the lasted upper by means of cement which is usually pyroxylin cement but may be of any other suitable kind. Pyroxylin cement forms a firm tenacious bond between the shoe parts which cannot be pulled apart by a direct pressure acting more or less 45 perpendicularly to the plane of the bond. However, in some cases where the extension edge of cemented shoes is subjected to severe downward knocking or scuffing, there may ensue a peeling action which peels the outsole away from

50 the upper to which it is cemented. That is, the cemented bond may sometimes be peeled or split apart where it could not ordinarily be directly pulled apart. In accordance with the present invention, this peeling separation of the outsole 55 from the upper is circumvented by deflecting or

altering the direction of the application of the separating force which is exerted when the edge of the sole is pressed downwardly away from the upper.

5 Referring more particularly to the drawing, there is shown an outsole 10 which may be made of any suitable sole stock. In fact, the bond obtained by following the principles of the present invention is so much stronger than those heretofore available that even coarse inferior grades of 10 leather such as belly leather, may be used with improved tenacity between the shoe parts, although a superior joint is assured when leathers of the commonly employed quality are used. The outsole 10 is rounded to any desired size, and is 15 given any of the usual desired operations prior to cement affixing it to the upper, such as shanking it out and roughing its marginal portion to which cement is to be applied.

20 In accordance with the present invention, the sole is provided with a channel or incision 11 which extends around a marginal portion thereof and runs downwardly into the sole stock from its flesh side. The primary function of this channel is to weaken the sole so that its edge portion may 25 flex downwardly away from its body portion so as to alter the effective direction of a force applied downwardly against the top edge of the sole after it is cemented to the shoe. This will be more apparent upon considering the shoe 30 structure illustrated in Fig. 2, which comprises an insole 12 to which an upper 13 is overlasted in the conventional McKay relationship except that its overlasted allowance 14 is preferably attached to the insole by cement indicated at 15. 35 However, the particular method of lasting the upper and insole makes no essential difference with respect to the principles of the present invention, so long as the outsole ultimately is cement bonded to the lasted upper. In the form 40 of shoe particularly illustrated in Fig. 2, a filler 16 is applied between the inturned edges of the lasting allowance and the outsole 10 is affixed thereto by a layer of cement 17, preferably pyroxylin cement, which is located between the marginal portion 45 of the sole and the inturned lasting allowance.

50 Channel 11 is extended downwardly and inwardly into the sole stock to a depth which is preferably at least half the thickness of such stock, or at any rate to such a depth that it facilitates downward flexure of the edge of the sole with respect to its central body portion. Some of the cement 17 seeps into channel 11 and serves normally to hold it closed. 55

However, the cement within channel 11 does not hold this channel closed with the same tenacity as the main body of cement holds the outsole to the upper. That is, when a force such as that indicated at F is applied to the edge of outsole, such edge flexes downwardly, opening the channel 11. Once this channel pulls open, the force F, which tended to peel the bond at 17, becomes applicable to such bond along a component indicated at F'. When the channel 11 is downwardly and inwardly directed, it will be seen that the force F must be transmitted around the thin flexed stock at 18 to a vicinity located within the point 19 where the channel 11 meets the flesh surface of the sole. In other words, the peeling effect of force F is altered to the direct pulling effect of force F' because of the opening of the gap at 11. In practice, the opening 19 of the channel is located about $\frac{3}{2}$ of an inch inwardly from the outermost boundary 20 of the cemented area, so that the peeling action exerted by force F can only continue for this $\frac{3}{2}$ of an inch, after which the channel pulls open and further exertion of the force must act directly downwardly against the adhesion of cement 17. This effectively circumvents continued peeling of the sole away from the upper which would render the shoe unfit for wear, and substitutes a relatively harmless local flexure of the edge portion of the sole. This edge portion is adapted to move back into position as soon as the force at F is removed.

The channel 11 may be extended around any desired marginal part of the outsole, being shown in Fig. 1 as extending around the forepart thereof, which is the preferred form. However, it may be extended along the shank and even into the heel portions if desired. This channel may be applied at any suitable time during the manufacture of the outsole, either before or after any of the usual operations, such as shanking, roughing, cementing, etc., and it may be made in any suitable manner, as for example by means of conventional channeling machines having a special knife, or having a conventional knife adjusted to the required angle. As explained, the channel preferably extends downwardly and inwardly in order to transfer the effect of downward scuffing forces to an area located well within point 19 at which the peeling action stops. However, it is contemplated that this channel may extend in any desired direction so long as the edge portion of the sole is weakened so as to permit downward flexure thereof in a manner which circumvents or retards a peeling separation of the outsole and upper.

It will be appreciated that in the drawing, the size and relationship of the parts has been exaggerated better to show the described non-peeling action.

It will be seen that in accordance with the pres-

ent invention, kicking and scuffing forces applied to the edge of the outsole of a cemented shoe cannot be effective to peel or pry the sole away from the upper and that a stronger and more permanent attachment between these shoe parts is as- 5

Since certain changes in carrying out the above method, and certain modifications in the article which embody the invention may be made without departing from its scope, it is intended that 10 all matter contained in the above description or shown in the accompanying drawing shall be interpreted as illustrative and not in a limiting sense.

It is to be understood that the following claims 15 are intended to cover all of the generic and specific features of the invention herein described, and all statements of the scope of the invention which, as a matter of language, might be said to fall therebetween.

Having described my invention, what I claim as new and desire to secure by Letters Patent, is:

1. A cemented shoe comprising an upper and an outsole, cement attaching said sole to said upper, said sole having a channel extending marginally around the forepart thereof, said channel opening into the flesh or upper surface of said outsole along a line located only slightly within the outer boundary of said cement, and continuing downwardly and inwardly into said sole 30 whereby the extended edge of said sole at the forepart is integrally attached to the remainder thereof at points located inwardly beyond the outer margin of said cemented area, said channel forming a weakened line around the forepart 35 margin of the sole so that said extended edge is held against the body of the sole with less tenacity than the sole is held against the shoe upper whereby downward forces applied to said extended edge may permit said channel to open to 40 assure transmission of such forces to said cemented area through said inwardly located integral attachment.

2. A method of preventing the outsole of a cemented shoe from peeling from the upper, which comprises weakening such outsole along a marginal line near the outer boundary of the cemented area by forming therein a weakened slit or channel from its flesh surface downwardly and inwardly toward but not to its grain side, applying cement to the flesh surface of the marginal portion of said sole while keeping said channel closed and excluding any save a possible slight seepage of cement from said channel, and sticking said cemented sole margin to the bottom of a lasted upper, whereby its outer edge portion beyond said weakened channel may break downwardly away from the body of the sole except at its integrally connected lower portion.
